STOP MOTION DEVICE FOR KNITTING MACHINES, PARTICULARLY FOR STRAIGHT-BAR KNITTING MACHINES

Jaroslav Václavík and Oldřich Bayer, Gottwaldov, Czechoslovakia, assignors to Zapadomoravské strojírny, národní podnik, Trebic, Czechoslovakia

Application October 5, 1954, Serial No. 513,831

Claims priority, application Czechoslovakia
October 6, 1953

15 Claims. (Cl. 66—163)

The present invention relates to a stop-motion for knitting machines, particularly straight-bar knitting machines, said stop-motion being so designed as to cause in the case of any incidental increase of the normal thread tension, underspooling, occurrence of slubs, breakage or absence of thread, an automatic displacement of the respective needle bar out of the range of the presser edge of the sinker head as well as the stoppage of the machine.

In a recently designed known arrangement of stop-motion devices on straight-bar knitting machines, through the functioning of electromagnetic or mechanical means any undue slackness in the thread, any occurrence of abnormal slubs, breakage or absence of thread bring about an angular displacement of a corresponding yarn detector, such motion resulting merely in a uniform substantial displacement of the needle bar in a direction away from the press. However, such considerable displacement of the needle bar frequently gives rise to breakdowns, as during knitting the initial rows of loops of a double welt of hosiery, when the welt bar is in the vicinity of the knitting needles, the loops of the initial courses are liable to slip out of the hooks of the welt bar needles as a result of the aforesaid displacement of the needle bar or it may also happen that the knitting needles are damaged by the hooks of the welt bar needles.

The present invention aims at eliminating the aforesaid drawbacks. Owing to an essentially more simple and convenient arrangement of the stop-motion, the resistance of the mobile elements and of the threads is reduced to a minimum so that the delicate stop-motion device can be used with absolute dependability for the control of particularly fine artificial silk or polyamide threads during knitting of any portion of hosiery. In this way, waste of material and time can be avoided and the production of low-grade hosiery can be prevented. The so-called topping-on and pressing-off hosiery throughout their width can be dispensed with, and this is particularly advantageous, as such topping-on operations take a much longer time than the re-threading of a broken thread, especially in artificial light.

The main feature of the new device in accordance with the present invention consists in that the displacement of the needle bar out of the range of the presser edge of the sinker head resulting from the change of position of any of the thread detectors or droppers of the stop-motion mechanism of a division is effected by the action of a central control mechanism which responds to different knitting operations employed in producing parts of a knitted article.

Details of the arrangement of the object of the present invention will be clear from the following description of an embodiment thereof stated by way of example with reference to the accompanying drawings wherein

Figs. 1a, 1b, 1c and 1d illustrate an elevational view of the general arrangement of the individual mechanisms according to the invention on a multi-division straight

2

bar knitting machine, as viewed from the back of the machine,

Figs. 2a and 2b a sectional view along the plane 1—1 in Fig. 1b during normal knitting,

Figs. 3a, 3b and 3c a detail "A" of the stop-motion mechanism as shown in Figs. 1a-1d provided above a division, including the central control mechanism,

Fig. 4 a fragmentary plan view of the detail A shown in Figs. 3a-3c,

Fig. 5 a detail "B" of the arrangement of the yarn detector according to Figs. 3a-3c during normal knitting,

Fig. 6 a detail "C" of the arrangement of the yarn detector according to Figs. 3a-3c in operative position,

Fig. 7 a section of a detail of the stop-motion device and of the central control mechanism along the plane 2—2 in Fig. 3a during normal knitting,

Fig. 8 the same section as in Fig. 7 at a moment of operation of the stop-motion device whilst the central control mechanism is at rest,

Fig. 9 the same section of a detail as in Fig. 7 after the completed operation of the central control mechanism of the stop-motion device,

Fig. 10 a sectional view of a detail of the arrangement of the safety mechanism of the stop-motion device along the plane 3—3 in Fig. 3a during the loop formation,

Fig. 11 a detail "D" of the arrangement of the machine stoppage device according to Figs. 1a-1d,

Fig. 12 a side view of the detail D according to Fig. 11 during normal knitting,

Fig. 13 the same side view of detail D as in Fig. 12 at the moment of its operation,

Fig. 14 is a side view of the control mechanism of the stop-motion device according to Figs. 3a-3c,

Fig. 15 a section of the needle bar release device along the plane 4—4 in Fig. 1d during normal knitting when the needle bar co-operates with the presser edge of the sinker head,

Fig. 16 a section along the plane 5—5 in Fig. 15,

Fig. 17 the same section as in Fig. 16 but in a position where the displacement of the needle bar out of the range of the presser edge of the sinker head is effected by the attendant during knitting the double welt,

Fig. 18 the same section as Fig. 15 but at a moment of interruption of the engagement of the press lever pin in the recess of the hand lever of the needle bar,

Fig. 19 the same section as Fig. 15 at a moment of a slight displacement of the needle bar in a direction away from the presser edge of the sinker head,

Fig. 20 the same section as Fig. 15 at a moment when the needle bar after its slight displacement returns to its normal position wherein it remains merely for knocking-over the loops of a course,

Fig. 21 the same section as Fig. 15 at a moment of a substantial displacement of the needle bar in a direction away from the presser edge of the sinker head.

The automatically operative device illustrated in the drawing is provided according to Figs. 1a-1d on a multi-division straight-bar knitting machine e. g. on a two-division machine whereof only those elements are shown in the drawings which are in connection with the object of the invention. Figs. 2a and 2b include, as far as the usual knitting elements are concerned, only the knitting needles 1 in the needle bar 2, the knocking-over bits 3 and the presser edge 4 of the sinker head 5. Close to

the needle row, the yarn carriers 6 are provided, travelling to and fro along a line of needles. Each thread 7 winding off above the head of the respective bobbin 8 arranged within a moistening box 9 of the machine is passing first the stop-motion mechanism 10 according to the invention and thereupon the well known tension device 11, the ring 12 serving as thread tensioner, the snap-

70

per assembly 13 and associated yarn carrier 6 up into the hooks of the knitting needles 1. There may be any convenient number of stop-motion mechanisms for each division of the machine.

The stop-motion device 10 (Figs. 6 and 8) of each thread consists of a stationary grid 14 and of a mobile dropper 15 supported with its pivot 16 in said grid 14 in such a way as to tend permanently to swing out of the operative position I into the inoperative position II. During the swinging movement of the dropper 15 about the pivot 16, its sidewall 17 (Fig. 8) acts upon a single-armed disconnecting lever 18 which projects into the path of movement of dropper 15. The operative position I of the dropper 15 is secured by the thread 7 (Fig. 6) which may be easily inserted topwise into a vertical groove 20 of the grid 14 by scizing the extension 19 and turning the dropper 15 into position III shown in Fig. 5. A leaf spring 21 fixed at one end of the grid 14 forms at its other free end an abutment for the dropper 15 in position III, wherefrom the dropper is brought back after the insertion of the thread into the groove 20 into a position close to position I. The operation of the dropper 15 in position I is not influenced by the leaf spring 21. A knife 22 which is adjustable in accordance with the thickness of the thread is fixed vertically at the entrance of the thread in the stop-motion mechanism 10 on the grid 14 so that it forms a clearance 23 with the grid 14 wherein any impurities or abnormal slubs occurring in a thread are caught up (Figs. 5 and 6). At the point where the thread leaves the grid, a pin 24 (Fig. 4) is provided about which the thread is guided before its entrance into a thread feeler 25.

The thread feeler 25 (Fig. 5) designed as a double-arm lever is arranged pivotally through a hub 26 on a pivot 27 between the grids 14, 15 and the tension device 11 (Fig. 2a). The straight arm of the thread feeler 25 is provided with an eyelet 28 for the passage of the thread 7 and the curved arm 29 of the thread feeler is able to act upon the respective disconnecting lever 18 (Fig. 8) in a similar way as the dropper 15 by projection of lever 18 into the path of movement of arm 29. A weight 30 adjustable on the curved arm 29 of the thread feeler 25 determines through its position the magnitude of the force necessary for the simultaneous angular displacement of all the levers 18 (Fig. 3b) of a division. Thus, for example, the weight 30 (Figs. 5, 6) with the thinnest thread is in a position close to the pivot 27 whilst with the thickest thread it is in a position at the free end of the curved arm 29. The number of the thread feelers 25 as well as the number of the grids 14, 15 fixed by means of screws on the horizontal wall of a cover 31 (Figs. 3b, 4) corresponds to the number of yarn carriers 6 for a division. The pivots 27 of the thread feelers 25 are fixed with their one end on the inner sidewall of a U-shaped cover 31 (Fig. 7) and with the other end in the lengthwise rim 32 extending parallel to the sidewall of the cover. The position IV of the thread feeler 25 (Fig. 5) during the normal operation is determined by the contact of its longer arm with the edge 33 of a recess 34 on the cover 31 (Fig. 4), the latter being provided above the moistening box 9 and fixed on two horizontal pins 35 (Figs. 2a, 4, 7). The offset end of each pin 35 is fixed in a horizontal angle iron 36 and secured by a nut (Fig. 2a). The angle iron 36 rests on two brackets 37 (Figs. 1a and 1b) of the moistening box 9. On each cover 31 two holders 38 (Figs. 2a, 4) are fixed for carrying two rods 39, 40 for guiding the thread, the thicker rod 39 being provided with horizontally extending apertures 41. The position V of the thread feeler 25 (Fig. 6) is brought about at an increase of the normal thread tension owing to a defective winding of the bobbin 8 or as a result of the occurrence of an abnormal slab. All the levers 18 of a division corresponding in number to that of the thread feelers 25 and grids 14, 15 are fixed at one end of

a horizontally extending rod 42 (Fig. 3b). The one end of the rod 42 is fixedly connected with a double-arm lever 43, the other end with a single-arm disconnecting lever 44. The lever 43 is pivotally supported on a pivot 45 fixed in the vertical wall 46 of the cover 31. The lever 44 is likewise pivotally supported on a pivot 47 fixed in the vertical wall 48 of the cover 31. The top end of the lever 43 is provided with two recesses 49, 50 (Fig. 7) and with a bent extension 51. The bottom end of each of levers 43, 44 extends into an equalizing arm 52 holding during normal knitting all levers 18 of a division in their position as shown in Fig. 7. In one or in the other of the recesses 49, 50 of the lever 43, a tooth 53 of a pawl 54 is engaged, said pawl being pivotally supported on a pivot 55 fixed in the vertical wall 46 of the cover 31. An equal spacing of the lever 43 and of the pawl 54 from the vertical wall 46 of the cover 31 is secured by means of spacing rings 56, wherethrough the pivots 45 and 55 (Fig. 3a) pass. The equalizing arm 57 of the pawl 54 provided with an adjustable weight 58 as well as the equalizing arms 52 of the levers 43, 44 secure the engagement of the tooth 53 of the pawl 54 in one or in the other of the recesses 49, 50 of the lever 43 (Figs. 7, 8). The other arm of the pawl 54 co-operates with the bent arm of the well known release needle 59 of D-shape (Fig. 7) provided at the rim of each division of the machine slidably mounted in a slide member 60 fixed at the free end of a shaft 61 (Fig. 3a). Each needle is arranged jointly for all the stop-motion devices 10 of a machine division. By the bent end of the release needle 59 fitting into the recess 62 (Fig. 7) of the slide member 60, the straight end of the needle 59 is prevented from dropping out of the slide member 60. Clockwise swinging of slide member 60 past the vertical position is prevented by a pin 63 provided in a bracket 64 fixed by means of bolts on an angle iron 36 (Figs. 1a, 1b, 2a, 3a). The shaft 61, provided with a setting ring 65 (Fig. 3a) carries a single-arm lever 66 wherein the one end of a tie rod 68 is suspended by means of a pin 67 (Fig. 2a). The other end of the tie rod 68 is secured by a pin 69 (Fig. 12) in a single-arm lever 70 fixedly connected to one end of a shaft 71. This shaft is supported in a freely turnable manner both in a bracket 72 of the sidewall 73 and in brackets 74 fixed on spacing rods 75 of the machine.

The lever 70 of a machine stop motion 76 (Fig. 12) cooperates with the pin 77 of a double-arm lever 78 supported pivotally on a pivot 79 of the bracket 72. A socket 80 fixed on the lever 78 carries a mercury switch tube 81 with welded-in contacts. The cables 82 lead to an electric motor not illustrated in the drawings. Through the pull of a coiled spring 83 secured at one end in a hinge 84 of the bracket 72 and with the other end in an opening of the lever 78, the pin 77 is urged against the bracket 72.

A single-arm lever 85 of the needle bar release device 86 (Fig. 1) fixed at the other end of the shaft 71 is provided with a notch 87 (Fig. 15), for the flattened end of the pin 88 of a three-arm lever 89, arranged pivotally on a pivot 90 of the bracket 74. A pivot 91 of the lever 89 is engaged in an elongated hole 92 of a double-arm lever 93 supported pivotally on a pivot 94 of the bracket 74. On the bent arm end of the lever 93 a cam roller 96 is rotatably arranged on a pivot 95 outside the range of an operative segment 97 fixed on a presser cam 98 provided on the main camshaft 99 (Fig. 16). A pin 100 (Fig. 15) fixed on the straight arm end of the lever 93 carries the end of a tie rod 101, the other end of which is secured on a pivot 102 of a hand-operated lever 103 supported pivotally on the machine shaft 104. The position of the cam roller 96 relative to the operative segment 97 is determined by the position of the pin 88 of the lever 89. The engagement of the pin 88 in the notch 87 of the lever 85 is secured by a coiled spring 105 suspended with one end in an aperture 106 of the lever 89 and with the other end in a hinge 107 of the bracket 74. A free narrowed

end 108 of the lever 89 is outside the range of an abutment 109 arranged pivotally on the pivot 110 of a hand lever 111 of the needle bar 2 (Figs. 16, 17). To this purpose, the abutment 109 is provided with a wider recess 112 wherein the pin 113 of the lever 111 is engaged. The lever 111 is arranged pivotally on a pivot 114 of a needle bar fork 123 and is provided with three notches 115, 116, 117 for the engagement of a pivot 118 of a press lever 119 supported pivotally on a carrier shaft 120. On the pivots 121 fixed in brackets 122 of the carrier shaft 120, the needle bar fork 123 is pivotally supported. On a pivot 124 fixed in the free end of the lever 119 a cam roller 125 is supported so as to ride on the circumference of the presser cam 98 of the main cam-shaft 99. A coiled spring 126 secured with the one end in a lug 127 on the fork 123 and with the other end in the lever 111 secures the engagement of any of the notches 115, 116, 117 with the pivot 118 of the lever 119. On the pivot 28 of the bracket 74 a stop lever 29 is pivotally arranged with its bent end 130 extending over the nose 131 of the abutment 109, whilst the straight end of the lever 129 fits against a set screw 132 of the bracket 74 (Figs. 15, 18, 19, 20). The respective position of the stop lever 129 is determined by a controlling drum 133 (Fig. 1d) supported rotatably on a fixed stub shaft 134 which may be carried by the sidewall 135. The periphery of the drum 133 comprises a cam projection 136 (Fig. 15) cooperating with a lever 137 supported pivotally on a pivot 138. A tie rod 140 mounted on a pivot 139 of the lever 137 is connected with the pivot 141 of a single-arm lever 142 attached to a shaft 143 freely turnable in the bracket 74. The levers 142, 144 fixed to the shaft 143 are linked up with the stop lever 129 of each machine division through a tie rod 145. Setting rings 146 (Fig. 1c) prevent the shaft from sliding laterally.

A central control mechanism 147 for all divisions of the machine is operated by the projection of any release needle 59 of a division out of the slide member 60 through the respective needle bar release device 86 of the securing mechanism 169 (Fig. 10) the disconnecting levers 18, 43, 44 and the machine stop motion 76, and consists of a single cam 148. This cam 148 bolted to a chain sprocket 149 (Fig. 3c) presents a lower and a higher circumference as can be seen in Fig. 14. The higher sprocket wheel 149 keyed on a shaft 150 is steadily driven through a link chain not illustrated in the drawings from a chain sprocket of the same size fixed on the main cam-shaft 99. On the circumference of a cam 148 rides a cam roller 151 supported rotatably on the pivot 152 of a single-arm lever 153. The lever 153 is pivotally supported on a pivot 154 fixed in the sidewall 135. A coiled spring 155 (Fig. 3c) attached with one end to an anchor 156 on the lever 153 and with the other end to an anchor 157 on the lever 153 provides for a permanent contact of the cam roller 151 with the circumference of the cam 148. The tie rod 159 pivotally connected at one end at 158 to the lever 153 is pivotally connected at the other end at 160 to a lever 161 fixed at the end of a shaft 162 supported rotatably in the bracket 37 of the moistening box 9 and in the holder 163 fixed on the angle iron 36 (Figs. 1b, 7). A lever 164 fixed at the other end of the shaft 162 is connected through a link 165 with a lever 166 on a shaft 167 of the bracket 64. An abutment segment 168 fixed on the shaft 167 cooperates with the straight end of the release needle 59 (Figs. 8, 9).

A securing mechanism 169 (Fig. 10) of the disconnecting levers 18, 43, 44 consists for each machine division of a double-arm securing lever 170 supported pivotally on a pivot 171 of the bracket 64. One wing-like arm end 172 of the lever 170 cooperates with the bent extension 51 of the lever 43. On the other arm end of the lever 170 fits the rounded-off end of a pusher member 173 supported slidably in the bracket 64. The other

thicker end of the pusher member 173 rides under the pressure of a coiled spring 174 on the circumference of a driver 175 fixed on the shaft 167 of the bracket 64. Instead of the pusher member 173 the free end of an L-shaped securing member 176 fixed to the slide member 60 of the release needle 59 can fit against both the arm of the securing lever 170 and the arm of the pawl 54 (Fig. 9).

The above described devices operate as follows:

During normal knitting of hosiery when each individual thread 7 is unwound through the reciprocating motion of the respective yarn carrier 6 (Fig. 26) over the head of the bobbin 8 and is guided with the help of the respective stop motion mechanism 10, a tensioning device 11, ring 12 and snapper assembly 13 into the knitting needles 2, the dropper 15 and the grid 14 are interengaged (position I in Figs. 5 and 6). The thread feeler 25 through the eyelet 28 of which passes the thread is in its position IV as shown in Fig. 5. The bent arm 29 of the thread feeler 25 is outside the range of the lever 18 which is in the position shown in Fig. 7, so that the arm 52 of the lever 43 and the arm 57 of the pawl 54 retain the tooth 53 of the pawl 54 in engagement with the top notch 49 of the lever 43. The bent arm of the release needle 59 rests against the bottom of recess 62 of the slide member 60 fitting against the pin 63 in its position shown in Fig. 7, without touching the arm of the pawl 54, so that the straight end of the needle 59 remains hidden inside the slide member 60. Likewise the free end of the securing member 176 for the levers 18, 43, 44 is outside the range of the arms of the pawl 54 and of the securing lever 170 which through the action of the pusher member 173 and pivotal driver 175 assumes the position shown in Fig. 7 during the sinking of each loop course. The reciprocating pivotal movement of the driver 175 and segment 168 of the central control mechanism 147 taking place after the completion of the sinking of each loop course in a direction towards, and away from, the slide member 60, is derived from the cam 148 (Figs. 1d, 3c, 14). During the sinking of each loop course, when the cam roller 151 of the lever 153 is riding inoperatively on the surface of the lower circumference of the cam 148 to the extent of a semi-circle, the segment 168 and the driver 175 remain in their position shown in Figs. 7 and 8. After the completion of the sinking operation, as soon as the yarn carrier 6 attains its extreme position alongside the needle bar 2, the cam roller 151 moves from the surface of the lower up to the higher semi-circular circumference of the cam 148 thus causing a pivotal movement of the segment 168 and driver 175 towards the needle 59 to the position shown in Fig. 10. In this operation, the higher semi-circular circumference of the cam 148 corresponds to that time which is necessary for the formation of a loop course. At the same time the pusher member 173 rides down from the higher to the lower circumference of the driver 175 thus releasing the securing lever 170. The wing 172 of the lever 170 falls behind the bent extension 51 of the lever 43 so that during the formation of each loop course, when no thread feed into the needles takes place, the lever 43 remains inoperative. After the completion of a course, when another sinking operation and consequently a new thread feed into the needles is taking place, the cam roller 151 rides off the higher down to the lower circumference of the cam 148 whereby the segment 168 is moved in a direction away from the needle 59 back to the position shown in Fig. 7. Simultaneously the pusher member 173 slides from the lower up to the higher circumference of the driver 175 so as to press against the arm of the securing lever 170. The wing 172 of the lever 170 is brought into a position outside the range of the lever extension 51 as shown in Fig. 7 so that the operation of the lever 43 is not impeded during the thread feed into the needles.

As a result of the inoperative position of the slide member 60 as shown in Fig. 7 as well as that of the shaft

61, lever 66 and tie rod 68 (Fig. 3a), the lever 70 (Fig. 11) fixed on the shaft 71 is outside the range of the pin 77 (Fig. 12) of the double-arm lever 78. Through the action of a coiled spring 83, the pin 77 fits against the bracket 72 so that the mercury switch tube 81 remains in its position shown in Fig. 12. To the aforesaid position of the slide member 60 or switch tube 81 as shown in Fig. 12 corresponds the position of the lever 85 as shown in Fig. 15. In this position the lever 85 retains the pin 88 of the three-arm lever 89 in such a way that the free narrowed end 108 of the lever 89 is underneath the abutment 109 of the hand lever 111 of the needle bar 2, the pivot 91 of the lever 89 moving the cam roller 96 of the lever 93 away from the operative segment 97. The engagement of the pivot 118 of the press lever 119 in the notch 115 of the lever 111 and the gliding motion of the cam roller 125 on the circumference of the press cam 98 result in the well known pressing motion of the needle bar.

During knitting of the initial courses of loops and double welt of hosiery, the straight end of the lever 129 fits against the adjustment screw 132 of the bracket 74 as a result of the action of the cam projection 136 of the controlling drum 133, levers 137, 142, 144 and tie rods 140, 145, the bent end 130 of the lever 129 being in a position above the nose 131 of the abutment 109 of the needle bar 2 (Fig. 15).

On an increase of the normal thread tension resulting from a defective winding of the bobbin 8, an impurity or from an abnormal stub caught up within the clearance 23 of the adjustable knife 22 which might result in a breakage of the thread, the thread feeler 25 is swung out of its position IV shown in Fig. 5 into position V shown in Fig. 6. During this movement the bent arm 29 of the thread feeler 25 presses against the respective lever 18 and brings all the levers 18 of a machine division from their position shown in Fig. 7 into the position shown in Fig. 8. As a result of such displacement of the levers 18, both levers 43 and 44 are brought from their position shown in Fig. 7 into their position shown in Fig. 8. The tooth 53 of the pawl 54 is simultaneously lowered from the top recess 49 into the bottom recess 50 of the lever 43, thus bringing about a displacement of the pawl 54 from the position shown in Fig. 8 as well as a lifting of the release needle 59 and shifting of its straight end out of the slide member 60. By the segment 168 being swung in the direction of the arrow (Fig. 8) at each completion of sinking a loop course through the cam roller 151 moving from the lower circumference up to the higher circumference of the cam 148, the slide member 60 is likewise swung from the position shown in Fig. 8 to the position shown in Fig. 9 by the segment 168 moving on to the projecting end of the needle 59. The needle 59 is lowered by gravity down to a point, where its bent end rests against the bottom of recess 62 of the slide member 60. The free end of the securing member 176 instead of the pushing member 173, which on the driver 175 being swung in a direction towards the needle 59, rides down from the higher to the lower circumference of the driver 175, holds the securing lever 170 in its original position shown in Fig. 9, wherein the wing 172 of the lever 170 is outside the range of the extension 51, as otherwise after displacement of the lever 43 into the position shown in Fig. 8, the wing 172 of the lever 170 would be unable to engage behind the extension 51 of the lever 43.

The angular displacement of the slide member 60 from its position shown in Fig. 8 into the position shown in Fig. 9 is transmitted through the shaft 61 (Fig. 1b), levers 66, 70 and tie rod 68 to the shaft 71. The angularly displacing lever 70 causes the pin 77 to be lifted and the lever 78 and switch tube 81 to turn about the pivot 79 into the position shown in Fig. 13 thus interrupting the electric circuit and stopping the machine.

Turning of the shaft 71 results in turning the lever 85

with the recess 87 from the position shown in Fig. 15 into the position shown in Fig. 19. Through the action of the coiled spring 105 the pin 88 of the lever 89 rides out of the recess 87 and this results in the lever 89 being turned about the pivot 90 from the position shown in Fig. 15 into the position shown in Fig. 18. The end 108 of the lever 89 acts upon the abutment 109 of the lever 111 and causes the lever 111 to turn about the pivot 114 into the position shown in Fig. 18, determined by the engagement of the nose 131 of the abutment 109 with the bent end 130 of the lever 129. As a result of such engagement maintained during the lowering movement of the needle bar and of the simultaneous disengagement of the pivot 118 with the notch 115 as shown in Fig. 18, whereupon the pin 118 of the lever 119 is unable to influence the position of the hand lever 111, a slight displacement of the needle bar 2 from its position VI shown in Fig. 15 to the position VII shown in Fig. 19 takes place. The riding motion of the cam roller 125 of the lever 119 along the higher circumference of the press cam 98 causes an inoperative angular shift of the pivot 118 of the press lever 119 from its position shown in Fig. 18 into the position shown in Fig. 19, without touching the notch 116 of the lever 111 thus avoiding pressing the knitting needles. The aforesaid slight displacement of the needle bar prevents an undesirable slipping of the first loop course out of the hooks of the double welt bar needles, not included in the drawings, and the knitting needles from being damaged on the hooks of the welt bar needles located close to the presser edge 4 of the sinker head 5. In view of the displacement of the lever 89 from the position shown in Fig. 15 to the position shown in Figs. 18 or 19, the pivot 91 thereof causes the simultaneous turning of the lever 93 about the pivot 94 from the position shown in Figs. 18 or 19, whereby the cam roller 96 is brought to rest against the circumference of the segment 97 on the rotating camshaft 99. The cam roller 96 is moved away from the shaft 99 and causes a temporary displacement of the levers 93 and 89 from the position shown in Fig. 19 to the position shown in Fig. 20, without enabling the pin 88 to enter the recess 87 of the lever 85. During the action of the segment 97 on the cam roller 96, the end 108 of the lever 89 is remote from the abutment 109 of the lever 111. The pivot 118 of the press lever 119 returns through the motion of the cam roller 125 along the lower circumference of the press cam 98 from the position shown in Fig. 19 to the position shown in Fig. 18. Through the action of the coiled spring 126 the pivot 118 of the lever 119 is brought into engagement with the notch 115 of the lever 111 so that the needle bar 2 returns during the formation of a loop course into the normal position VI shown in Figs. 15 or 20, wherein the descending knitting needles are forming loops, without giving rise to the possibility of the loops getting torn through the influence of the curved back of the knock-over-bits 3. During knitting of the following loop courses, the cam roller 96 rides down from the circumference of the segment 97 and the coiled spring 105 causes a new turning of the levers 89, 111 and a slight displacement of the needle bar 2 into the position VII shown in Fig. 19 at which the machine is brought to a stop.

The turning of the levers 89, 93 from the position shown in Fig. 19 or 21 into the position shown in Fig. 15 wherein the pin 88 of the lever 89 is again introduced into the recess 87 of the lever 85, is brought about by the attendant 65 by seizing and lifting the hand lever 103 about the machine shaft 104. Turning of the levers 70, 85 and of the shafts 61, 71 causes the slide member 60 and needle 59 to return from the position shown in Fig. 9 to the previous position shown in Fig. 7 determined by the contact between the slide member 60 and pin 63. Through the action of the coiled spring 83 the lever 78 is turned into the previous position shown in Fig. 12 so that its pin 77 is again brought to rest against the bracket 72 and the switch tube 81 to assume its horizontal inoperative position. The weight of the arms 52, 57 causes the pawl 54, levers 18, 43, 44 as

well as the thread feeler 25 to return to their normal position IV as shown in Figs. 5 and 7.

The hand-operated displacement of the needle bar 2 through the lever 111 from position VI to position VIII shown in Fig. 21 after stopping the machine for facilitating the access to the knitting needles during knitting of the initial courses of loops and double welt is enabled by the abutment 109 being pivotally arranged about the pivot 110 of the lever 111 (Fig. 17). During this operation the bent end 130 of the lever 129 is above the nose 131 of the abutment 109 and the pin 88 of the lever 89 is engaged in the recess 87 of the lever 85. The lever 111 is turned upwards by pressing its handle about the pivot 114 in a downward direction, the nose 131 of the abutment 109 passing between the end 130 of the lever 129 and the narrowed end 108 of the lever 89 from the position shown in Fig. 16 to the position shown in Fig. 17.

In the case of the thread 7 being completely unwound from the bobbin 8, the free thread end leaving the grids 14, 15 causes the dropper 15 to move about the pivot 16 from the operative position I to the inoperative position II shown in Figs. 6 and 8. This results in the sidewall 17 of the dropper 15 pushing the respective lever 18 and turning all levers 18, 43, 44 of a machine division in the aforesaid manner, resulting in a displacement of the needle bar from its position VI shown in Fig. 15 either to the position VII shown in Fig. 19 during knitting of initial courses of loops and the double welt or to the position VIII as shown in Fig. 21 during knitting the remaining portions of a stocking and in the stoppage of the machine.

After knitting the double welt, the end of the lever 137 through the movement of the controlling drum 133 in the direction of the arrow shown in Fig. 21 rides down from the surface of the cam projection 136 to the surface of the drum 133 resting thereon up to the completion of the knitting of the whole stocking. The aforesaid movement of the lever 137 about the pivot 138 is transmitted through the rods 140, 143 and levers 142, 144 to the stop lever 129 pivoted about the pivot 128 from the position shown in Fig. 15 into the position shown in Fig. 21. The bent end 130 of the lever 129 is brought out of the range of the nose 131 of the abutment 109 so that in the case of the aforesaid displacement of the lever 89 from the position shown in Fig. 15 into the position shown in Fig. 21 its narrow end 108 is enabled through the action on the abutment 109 of the lever 111 to cause the displacement of the latter about the pivot 114 into the position shown in Fig. 21 determined by the interengagement of the pivot 118 of the the press lever 119 and the notch 117 of the lever 111. Through the aforesaid displacement of the lever 111 the needle bar fork 123 is simultaneously swung about the pivots 121 into the position shown in Fig. 21. The return of the lever 89 into the previous position shown in Fig. 15, wherein the pin 88 is again engaged in the recess of the lever 85 as well as the return of the needle bar 2 from position VIII shown in Fig. 21 into the normal position VI shown in Fig. 15 is achieved by the attendant in the manner above described.

Through the displacement of the dropper 15 from position II in Fig. 6 to position III shown in Fig. 5 a new thread can be easily introduced top wise into the vertical groove 20 of the grid 14 and clearance 23 of the knife 22.

The present invention is in no way limited to the embodiment described and illustrated merely by way of example but can be applied with slight modifications to a multi-division straight-bar knitting machine without departing from the scope of the invention. It is also possible to apply the idea of the invention to other machines with similar working conditions, such as flat knitting machines, etc.

We claim:

1. A stop motion for a multi-division, straight bar knitting machine of the type performing sequential

operations during which the machine produces two differently knitted parts of knitted articles, and having means for driving the machine, a needle bar movable out of the range of the presser edge of the sinker bed and a thread guide movable to and fro along the needles of each division of the machine; said stop motion comprising, in each machine division, a thread guard mechanism including a movable thread feeler and a movable grid for each thread and engaged by the latter for movement from related normal positions by an incidental increase of the normal thread tension and knotting and by underspooling, breakage and running down of the related thread, respectively, a central control mechanism actuated by the movement of any of said thread feelers and grids from the normal positions thereof and operative to deflect said needle bar to a selected one of two different positions out of the range of the presser edge of the sinker bed corresponding respectively to the two differently knitted parts of knitted articles produced by the machine and to halt said driving means, and means sensing the operation being performed by the machine at the time of the actuation of said control mechanism and influencing the latter so that the needle bar is moved to that one of said positions out of the range of the presser edge corresponding to the machine operation then being performed.

2. A stop motion according to claim 1; wherein said thread feelers are individually rockable, and said control mechanism includes a series of disengagement levers associated with said thread feelers and engageable by the latter upon movement of the related thread feelers away from said normal positions of the latter, a rockable support structure carrying said disengagement levers and rocked by engagement of any one of said disengagement levers by the related thread feeler, said support structure including a rockable, notched lever, and a rockable pawl engageable with said notched lever and angularly displaced in response to rocking of said notched lever with said support structure.

3. A stop motion according to claim 2; wherein said movable grids are individually rockable and held in said normal positions thereof by engagement with the related threads, said grids being biased away from said normal positions thereof so that, upon release of the related thread, the grid moves away from its normal position, each of said grids being associated with a related one of said disengagement levers and engaging the related disengagement lever to rock said support structure upon movement of the grid from its normal position.

4. A stop motion according to claim 3; wherein said support structure includes a rod on which said disengagement levers are fixed and secured, at one end, to said notched lever, a second lever secured to the other end of said rod, said notched and second levers being pivotally mounted and having equalizing arms gravitationally urging the support structure to rock in the direction opposed to the rocking thereof caused by engagement of one of said disengagement levers by the related thread feeler or grid.

5. A stop motion according to claim 4; wherein said pawl is angularly biased in one direction, and said notched lever has two notches alternately engaged by said pawl and in stepped arrangement at different distances from the rocking axis of said support structure, said pawl normally engaging in one of said notches and being angularly displaced into the other of said notches by the bias acting on the pawl when said notched lever is rocked in response to engagement of one of said disengagement levers by the related thread feeler or grid, said notched lever further having a bent extension, and a securing lever engageable with said bent extension to prevent rocking of said notched lever and the remainder of said support structure by engagement of one of said thread feelers and grids with the related disengagement lever.

6. A stop motion according to claim 5; wherein said pawl is engageable with a release needle which is slideable in a rockable slide member and is projected from the latter by engagement of said pawl in said other notch of the notched lever, a continuously oscillated abutment segment engageable with said release needle when the latter projects from said slide member to rock the latter, a cam rotated in synchronism with the movement of the thread guide to and fro along the needles of the division of the machine, and transmission means between said cam and said abutment segment to oscillate the latter in synchronism with the to and fro movement of the thread guide so that said slide member is rocked only when said thread guide is disposed at one of the extreme ends of the related machine division.

7. A stop motion according to claim 6; wherein a pusher member is engageable with said securing lever and is actuated by a cam segment oscillated with said abutment segment, said cam segment being formed to effect engagement of said securing lever with said extension of the notched lever during loop formation and to effect angular displacement of said securing lever out of engagement with said notched lever during the sinking of the loops.

8. A stop motion according to claim 7; further comprising a securing member extending from said slide member and acting against said pawl and said securing lever to hold said pawl and securing lever out of engagement with said notched lever during the interruption of the thread feed following the rocking of said slide member by engagement of said abutment segment with the projected release needle.

9. A stop motion according to claim 8; wherein said control mechanism further includes a manually operable deflecting lever connected to the needle bar, a needle bar disconnecting device including two normally interengaged levers, one of said interengaged levers having a tension spring connected thereto for angular movement which is normally resisted by the other of said interengaged levers, means actuated by rocking of said slide member to free said interengaged levers, and means transmitting the spring urged angular movement of said one interengaged lever to said deflecting lever upon freeing of said one interengaged lever from said other interengaged lever.

10. A stop motion according to claim 9; wherein said means transmitting the angular movement of said one interengaged lever to said deflecting lever includes a stop on the latter, an end of said one interengaged lever lifting said stop in response to said angular movement of said one interengaged lever; and wherein said control mechanism further includes a press lever having a pivot thereon, said deflecting lever having a recess therein normally receiving said pivot of the press lever and from which said pivot is disengaged upon lifting of said stop, thereby to provide for simultaneous displacement of said deflecting lever and deflection of the needle bar out of the range of the presser edge on the sinker bed.

11. A stop motion according to claim 10; wherein said means sensing the operation being performed and corre-

spondingly influencing said control mechanism includes a rotated control drum having peripheral portions corresponding to the operations performed by the knitting machine, a follower engaging said control drum, a stop lever controlling the magnitude of the angular displacement of said deflecting lever and thereby the magnitude of deflection of the needle bar, and transmission means between said follower and said stop lever so that the magnitude of the angular displacement of said deflecting lever and of the needle bar permitted by said stop lever depends upon the peripheral portion of said control drum then engaged by said follower.

12. A stop motion according to claim 11; wherein said control mechanism includes an electrical circuit connected with the driving means and having a mercury switch interposed therein and a rockable support for said mercury switch, and said means actuated by rocking of the slide member to free the interengaged levers includes a rocked arm engageable with a pin on said switch support to rock the latter to an inclined position where the circuit through said mercury switch is interrupted to halt the driving means.

13. A stop motion according to claim 11; wherein, during the performance of one operation by the machine said stop lever is disposed, by said control drum, follower and transmission means, in a position where an end of said stop lever is disposed under said stop of the deflecting lever to form a level limit for said stop thereby restricting the angular movement of the deflecting lever to an extent sufficient to produce only a small needle bar deflection.

14. A stop motion according to claim 13; wherein, during the performance of the other operations by the machine, said stop lever is displaced, by said control drum, follower and transmission means, to a position wherein said end of the stop lever is withdrawn from the path of said stop on the deflecting lever, thereby permitting deflection of the needle bar to a position relatively far from the presser edge, said deflecting lever having a second recess therein receiving said pivot of the press lever when the needle bar is moved to said position relatively far from the presser edge and thereby determining the last mentioned position of the needle bar.

15. A stop motion according to claim 13; further comprising a rotated cam segment, a cam follower roller, a lever pivoted to said one interengaged lever and carrying said cam follower roller to move the latter against said rotated cam segment in response to the displacement of said end of said one interengaged lever against said stop whereupon said rotated cam segment, follower roller and the lever carrying the latter cause rocking of said end of the one interengaged lever away from said stop to permit the return of the slightly deflected needle bar to its normal position adjacent the presser edge of the sinker bed during the loop formation of at least one row of loops prior to the halting of the driving means.
